CONVERTIBLE SKIRT

Louis M. Sever, Los Angeles, Calif.

Application May 16, 1946, Serial No. 670,143

6 Claims. (Cl. 2-213)

1

My invention relates to a woman's garment. The object of my invention or inventions, which are disclosed and described herein, is to provide a lady's garment of a convertible nature which will have both a dual purpose and a dual appearance. These desirable features are attractively and efficiently combined in one garment, which may be of a skirt type or a garment including a lower portion functioning as a skirt and having a conventional dress-like appearance.

The construction features and advantages that are original, distinctive, and found only in my design are these: in conjunction with the skirt is provided fabric which is supported by and hangs from the waist line and which is sewed longitudinally through the center to form a crotch as well as being joined with the outer two halves of fabric which comprise the skirt. Two leg portions are thus formed which have the appearance and utility of loose trousers, or a split skirt. Means for fastening and unfastening, which may be slide fasteners ("zippers") or the like, are attached vertically to the center front and center back at the points in the garment where the outer skirt portion separates. The fasteners above mentioned may be used to join the two leg portions together in the front and back, creating the pleasing outward appearance of a nicely tailored skirt. Upon opening the fasteners by moving the slideable members upward to the desired height, the division takes place and the garment becomes a split or divided skirt. In this way the garment is made usable and is well suited for wear in active sports, etc., where an ordinary skirt would not be practical or appropriate.

One of the two slide fasteners (preferably the one in front) which, when open, helps to divide the skirt portion may be of the completely separating type and be also used for separating the garment at the top of the waist band, permitting the wearer to put on or take off the garment, thus eliminating the necessity of a separate placket, or fastener, for that purpose. The fasteners provided in the front and back of the garment may be operated individually to close the divided skirt, to in turn open it for active use, or, if it is desirable, to produce the effect of kick pleats, either in the front or back, or

both, said fasteners may be raised partially to obtain the proper results.

In order to avoid the bulky and droopy appearance commonly found in and about the crotch portion of an ordinary divided skirt, I have made use of novel and unique methods in cutting, folding, and supporting the fabric. Means of expansion are provided at the waist line which allows the wearer to put on and take off the garment with ease. The above methods, which are original in my design, create a well fitting and comfortable garment without involving the use of any excess material.

The general construction of my garment is such that the outer skirt portion is held in by and supported at the waist line as though it were a regular skirt. The inner portion of the garment, which provides a covering for the thighs and upper legs and closely conforms to the shape and contour of those parts of the body, is also securely held in place by support from the waist line. In this way, these two major portions independently maintain their proper shape and yet conform with each other without drooping or bunching as might otherwise result. The natural rigidity of the slide fasteners and the particular way in which they are used help in the support and alignment of the fabric down the front and back of the garment.

In the accompanying illustrations and descriptions various designs and adaptations are shown. The basic construction lends itself to many different styles, practical applications, and uses. Cottons, rayons, woolens, or any fabric suitable for active sports wear may be used in its manufacture.

The principles involved and so illustrated and described constitute the basis of my invention.

Referring to the drawings:

Fig. 1 is a view as seen from the front of the wearer of the garment when it is used as a skirt; Fig. 2 is a similar view as seen from behind the wearer;

Figs. 3, 4, 5, and 6 are views showing the patterns of various crotch members;

Fig. 7 is a plan view as seen from above, of the waist line of the garment with no pleats at this line;

Fig. 8 is a sectional view on a plane indicated by the line K-K of Fig. 12, showing how the

3

legs of the garment are formed, this plane being viewed in the direction of the arrows adjacent the line K—K of Fig. 12;

Fig. 9 is a plan view of the waist line of the garment in the position it finally assumes when adjusted for wearing by the user;

Fig. 10 is a plan view of the waist line of the garment in place on the wearer but not finally adjusted;

Fig. 11 is a section on a plane passing through the center of the garment;

Fig. 12 is a view of the garment as seen from the front of the wearer of the garment when it is used as trousers; and

Fig. 13 is a similar view as seen from behind the wearer.

In its simplest form the garment includes eight fabric members numbered in the drawings from 1 to 8. These parts are sewed together as herein-after described and are provided with a crotch "zipper" 9, a front "zipper" 10, and a rear "zipper" 12. The terms "right" and "left" as used herein-after denote position in relation to the wearer of the garment.

The members 2 and 3 are sewed together along a seam 23 to form a left outer panel 24, and the members 1 and 4 are sewed along a seam 25 to members 1 and 2 are connected by the front "zipper" 10, which is of the type which fully disengages at the end of its travel. The "zipper" 10 is pulled upwardly from the bottom 27 or knee line K—K to the top 28 or waist line W—W of the front of the garment to disengage the members 1 and 2.

The rear "zipper" 12 extends from a point 29 somewhat below the top 28 of the garment to the bottom 27 thereof and is pulled upwardly to disengage the members 3 and 4. With the "zippers" 10 and 12 fully engaged, the garment has the appearance of a skirt, as shown in Figs. 1 and 2.

The members 6 and 7 are sewed together along a seam 30 to form a left leg panel 31, and the members 5 and 8 are sewed together along a seam 32 to form a right leg panel 33. The left leg panel 31 is sewed at the front along a seam 34 and at the back along a seam 35 to the left outer panel 24. The right leg panel 33 is sewed at the front along a seam 36 and at the back along a seam 37 to the right outer panel 26. The panels 24 and 31 form a left leg and the panels 26 and 33 form a right leg of the garment. The seams 34 and 35 are sewed together in a seam 40 on the back of the garment from the top 28 down to the point 29, as shown in Fig. 2, and from there to the bottom of the garment they are secured together by the rear "zipper" 12. The seams 34 and 36 are secured together throughout their entire length by the front "zipper" 10, and by pulling the "zipper" 10 entirely out of engagement the seams 34 and 36 may be entirely disengaged from each other. The members 5 and 6 may be joined together at the front by a front crotch seam 41, and the members 7 and 8 may be joined together by a rear crotch seam 42. I prefer, however, to substitute for parts of the seams 41 and 42 the crotch "zipper" 9. This "zipper" extends from a point just below the top at the back of the garment to a similar point on the front. It will be noted from Fig. 8 that the outer panels 24 and 26 are much wider at the lower end of the garment than the leg panels 31 and 33.

The top of the garment is encircled by a belt 50 having a conventional buckle 51, as shown in

4

Fig. 9. The members 8 and 7 are each folded to form a back pleat 52 so that the seam 42 coincides with the seam 40, and this pleat is stitched together at the top of the garment. An elastic band 53 is secured at the seam 41, which joins the members 5 and 6, and one end of this band is fastened at 54 to the member 1 and the other end is fastened to the member 2 at 55. The band 53 acts as a belt to hold the outer panels 24 and 26 against the hips of the wearer when the front "zipper" 10 is disengaged. Perhaps more important, it supports the top portion of the members 5 and 6 to form a front pleat 60 due to the seams 34 and 36 being drawn together. The garment may be easily pulled up over the hips of the wearer, the pleat 60 being pulled open and the members 5 and 6 being drawn from their folded position in the pleat 60, as shown in Fig. 9, into an extended position, as shown in Fig. 7. The member 53 may be a non-elastic tape fastened with snap fasteners or buttons at 54 and 55 to the members 1 and 2. When the garment is assembled, the pleat 52 formed by the upper ends of the members 7 and 8 is sewed permanently in place.

The garment shown in the drawings extends only from the waist of the wearer to a point near the knees. Obviously, the garment could be made of ankle length, and it is also obvious that an upper sleeved portion could be added to the garment and that the front "zipper" 10 could be extended to join the edges of this upper portion.

While I have shown and described the use of "zippers" as fastening means, it is obvious that buttons, lacings, or other well known fastening means are mechanically equivalent to "zippers" and may be substituted therefor.

The peripheral portion of the garment formed by the members 1, 2, 3, and 4 forms a complete skirt. The members 5, 6, 7, and 8 form the crotch portion of the garment, the crotch itself being formed by the seams 41 and 42. This crotch portion resembles a pair of trousers with a strip removed down the outer portion of each thigh and leg of the wearer.

The circumferential waist length, that is, the length around the waist of the wearer, is that shown in Fig. 10 and is equal to the total width of the members 1, 4, 3, 2, 6, and 5 at their upper ends, less allowance for seams. This circumferential waist length is sufficient to allow the garment to be drawn up over the hips of the wearer, and when it is in place the elastic member 53 tends to draw the seams 34 and 36 together and thus shorten the circumferential waist length so that the garment fits about the waist of the wearer and is supported by the tops of the hips. The elastic member 53, being attached to the crotch portion at the seam 41, tends to hold this crotch portion up. The circumferential waist length can be further shortened by the belt 50 and its buckle 51 so that it fits tightly about the waist of the wearer. When the circumferential waist length is fully shortened, as shown in Fig. 9, the seams 34 and 36 are drawn together and fastened together by the front "Zipper" 10, and the pleats 52 and 60 fold automatically into place.

I claim as my invention:

1. A garment comprising: a peripheral portion forming a skirt; a rear slide fastener extending only from the bottom of said skirt to a point somewhat below the top of the garment; a front slide fastener extending from the bottom of the garment to the top thereof and so constructed that it is entirely released at the top of its travel;

a crotch portion secured at the waist line to said skirt in such a manner as to form a garment having a continuous waist portion including portions of said crotch portion, said waist portion having a circumferential waist length sufficient to allow the waist encircling portion thereof to be pulled upwardly past the hips of the wearer; and an elastic tape situated at the waist line at the front thereof and secured at each end to said skirt and crossing those portions of the waist line occupied by the waist encircling portion of said crotch portion, said tape being secured near its center to the center of that portion of the crotch portion which forms a part of the waist line of the garment at this point, said tape constricting said garment at the waist line to fit about the waist of the wearer of the garment.

2. A garment comprising: a peripheral portion forming a skirt; a rear slide fastener extending only from the bottom of said skirt to a point somewhat below the top of the garment; a front slide fastener extending from the bottom of the garment to the top thereof and so constructed that it is entirely released at the top of its travel, said front slide fastener when engaged connecting the inner front edges of the skirt from its waist line to its knee line; a crotch portion secured at the waist line to said skirt in such a manner as to form a garment having a continuous waist portion including portions of said crotch portion, said waist portion having a circumferential waist length sufficient to allow the waist encircling portion thereof to be pulled upwardly past the hips of the wearer; and an elastic tape situated at the waist line at the front thereof and secured at each end to said skirt and crossing those portions of the waist line occupied by the waist encircling portion of said crotch portion, said tape being secured near its center to the center of that portion of the crotch portion which forms a part of the waist line of the garment at this point, said tape constricting said garment at the waist line to fit about the waist of the wearer of the garment.

3. A garment comprising: a split skirt having a front pair of edges which extend from the hem of said skirt to the waist thereof, and having a rear pair of edges which extend from the hem thereof to a point intermediate the hem and waist thereof; an expansible pleat connected to said skirt on the inside thereof and extending downwardly from the waist of said skirt adjacent said front pair of edges; front fastening means for securing the edges of said front pair together, said front fastening means being releasable from the hem of said skirt to the waist thereof to permit expansion of said pleat whereby said skirt may be pulled upwardly past the hips of the wearer; a belt member on the inside of said skirt at the waist thereof, said belt member being connected at its ends to said skirt and being connected intermediate its ends to said pleat to prevent sagging of said pleat; and rear fastening means for securing the edges of said rear pair together.

4. A garment comprising: a split skirt having a front pair of edges which extend from the waist of said skirt to the hem thereof, and having a rear pair of edges which extend from the hem of said skirt to a point intermediate the hem and waist thereof; an expansible front pleat connected to said skirt on the inside thereof and extending downwardly from the waist of said skirt adjacent said front pair of edges; a rear pleat connected to said skirt on the inside thereof and

extending downwardly from the waist of said skirt; front fastening means for securing the edges of said front pair together, said front fastening means being releasable along the entire length of the edges of said front pair to permit expansion of said front pleat whereby said skirt may be pulled upwardly past the hips of the wearer; a belt member situated on the inside of said skirt at the waist thereof, said belt member being connected at its ends to said skirt, and being connected intermediate its ends to said front pleat to keep said front pleat from sagging; and rear fastening means for securing the edges of said rear pair together.

5. A garment comprising: a split skirt having a pair of front edges which extend downwardly from the waist of said skirt to the hem thereof for the full length of said skirt, and having a pair of rear edges which extend upwardly from the hem of said skirt to a point intermediate the hem and waist thereof; a crotch portion inside said skirt and connected to said skirt at the front and rear thereof, said crotch portion cooperating with said skirt to form front and rear pleats which extend downwardly from the waist of said skirt; front fastening means for securing said front edges of said skirt together, said front fastening means being releasable along the entire length of said front edges to permit expansion of said front pleat, whereby the waist of said skirt is enlarged sufficiently so that said skirt may be pulled upwardly past the hips of the wearer; an elastic belt member situated inside said skirt at the waist thereof, said elastic belt member being connected at its ends to said skirt and being connected intermediate its ends to said front pleat to constrict the waist of said skirt and to prevent sagging of said front pleat and said crotch portion; and rear fastening means for securing said rear edges of said skirt together.

6. A convertible garment intended to perform a double function, that is, to serve as a skirt and to be readily convertible into trousers, comprising: a right-hand skirt panel whose upper edge has a length approximately equal to half the circumferential distance around the waist of a prospective wearer; a right-hand trouser panel recessed downwardly from its upper edge to form a space to receive the crotch of said wearer; a right-hand front seam joining the front edge of said right-hand trouser panel to the front edge of said right-hand skirt panel; said right-hand panels being so joined by said right-hand front seam so that the upper front edge of said right-hand trouser panel forms a front extension of the upper edge of said right-hand skirt panel; a right-hand back seam joining the back edge of said right-hand trouser panel to the back edge of said right-hand skirt panel; a left-hand skirt panel whose upper edge has a length approximately equal to half the circumferential distance around the waist of a prospective user; a left-hand trouser panel recessed downwardly from its upper edge to form a space to receive the crotch of said wearer; a left-hand front seam joining the front edge of said left-hand trouser panel to the front edge of said left-hand skirt panel, said left-hand panels being so joined by said left-hand front seam that the upper front edge of said left-hand trouser panel forms an extension of the upper edge of said left-hand skirt panel; a left-hand back seam joining the back edge of said left-hand trouser panel to the back edge of said left-hand skirt panel; a crotch seam joining the edge of the recessed crotch portion of said right

trouser panel to the edge of the recessed crotch portion of said left-hand trouser panel; readily detachable closure means for securing the front edge of said right-hand skirt panel to the front edge of said left-hand skirt panel; an elastic member secured at its center to the upper front edge of one of said trouser panels near its juncture with the other trouser panels, said elastic member extending parallel to the upper or waist edge of the garment, one end of said elastic member being secured to said right-hand skirt panel near the upper edge thereof and the other end of said elastic member being secured to said left-hand skirt panel near the upper edge thereof; and a belt passing around and engaging the upper edge of the garment. 15
